OLLIVIER MARIE GUSTAVE DE L'HARPE, OF PARIS, FRANCE, ASSIGNOR TO SOCIETE
FRANCAISE RADIO ELECTRIQUE, OF PARIS, FRANCE

REGULATOR FOR AMPLIFIERS

Application filed January 15, 1926, Serial No. 31,399, and in France July 22, 1925.

The invention concerns an amplifying system and has for its principal object to provide such a system in which the amplification factor shall change inversely with respect to the power applied to its input circuit.

Another object of the invention is to provide such a system in which the amplification will vary in inverse ratio to persisting changes in the applied power but will not so vary on instantaneous changes.

Still another object of the invention is to provide such a system in which an amplifying device has a resistance in its input circuit which will automatically increase in value with increase of current.

Still another object of the invention is to provide an amplifying device having a resistance in its input circuit which will vary in value directly with the amount of current flowing therethrough but whose variations will be subject to an appreciable time lag.

The invention has been found particularly useful in connection with automatic regulators for amplifiers used in connection with modulators in radio transmitting stations, although it should be understood that it is not limited to this use. In broadcasting programs from such stations it has been the custom to manually control the amplification to improve the quality of the music or other material being broadcasted. This is necessary on account of the different ways in which different parts of a musical selection, for example, are rendered. If certain portions of a selection are played with greater vigor thereby impressing an excessive volume of sound on the microphone, an effect known as "blasting" results causing a very disagreeable noise due to the overloading of the apparatus. On

the other hand, if portions of the music are being played softly, it may be very difficult for operators of broadcast receivers to hear them distinctly. In the former case, the amplification is decreased in the transmitting station and in the latter case it is increased by the proper amount. This volume regulation or "monitoring" is not altogether satisfactory because the operator naturally only corrects the undesirable features in the rendition of the program after they have begun to

be apparent. Under the present system I provide for automatic monitoring. This may be accomplished in a multi-stage amplifier by transferring the current to be amplified from one stage to the succeeding one across a resistance which will increase in value with the intensity of current flowing therethrough. It has been found that an incandescent lamp with a metallic filament and of suitable rating can be used advantageously for such a resistance. This arrangement owing to the increase in resistance when large currents are flowing automatically reduces the amplification for large amounts of power and increases it for small amounts of power. A further advantage of such a resistance resides in the fact that this resistance does not change instantaneously with increase of current but only after an appreciable time interval. This, as will be explained hereinafter, is an important feature of the invention.

The invention is illustrated by way of example in the accompanying drawing in which the single figure represents a diagrammatic circuit arrangement according to the invention.

Referring to the drawing a two stage amplifier is shown consisting of two three electrode vacuum tubes L_1 and L_2 connected together in cascade. The cathodes of these tubes may be connected in parallel and energized from a common source A. A common plate battery B is provided to supply the plate current of both tubes. The current to be amplified is applied to the terminals 1, 2 and transferred to the input circuit of the tube L_1 across the transformer T_1 . The plate circuit of this tube is connected to the battery B through a resistance R_1 and the primary of a transformer T_2 is connected through a condenser C to a point between the resistance R_1 and the plate of the tube L_1 , the other terminal of this transformer primary being grounded as at G. The amplified current in the plate circuit of the tube L_1 is transferred to the input circuit of the tube L_2 by means of a transformer T_3 whose secondary is connected across the filament and grid of the tube L_2 and may be shunted by a resistance R_2 if desired. The primary of

the transformer T_3 is connected to the secondary of the transformer T_2 , a resistance R_3 whose function will be explained in detail hereinafter being inserted in series in the circuit. The amplified current in the plate circuit of the tube L_2 may be used to energize any desired device, shown in the present case as an inductance Y . This inductance may be any desired apparatus which it is desired to operate. It may, on the other hand, be the primary of an additional transformer leading to other stages of amplification.

The resistance R_3 which in effect is in series in the circuit connecting the tube L_1 to the tube L_2 is so chosen that it will increase with the intensity of the current which traverses it. As explained above an incandescent lamp with a metallic filament can advantageously be used for this resistance. The effect of this resistance can be best explained by a simple numerical example. It may be chosen so that if E designates the voltage across the secondary of the transformer T_2 , E' the voltage across the primary of the transformer T_3 , and I the current in the resistance R_3 , the following values will be obtained:

$$\begin{array}{lll} E=1 \text{ volt} & I=1 \text{ ampere} & E'=0.5 \text{ volts} \\ E=100 \text{ volts} & I=10 \text{ amperes} & E'=5 \text{ volts} \end{array}$$

It will be seen that with such an arrangement the amplifying power of the system will be ten times greater for small amplitudes than for large ones. It is, of course, possible to obtain an even greater variation in amplifying power by suitably choosing the resistance R_3 .

It is understood that the number of stages of the amplifier can be as desired and that the method of connecting between stages is adapted to wide variations. Moreover, the arrangement can be applied if desired between several successive stages of a multi-stage amplifier or only between two particular stages of such an amplifier. The two stage amplifier illustrated with its particular connections is given merely by way of example.

It should be noted that a very important advantage of the device results from the calorific inertia of the metallic resistance R_3 which will be of the order of several hundredths of a second. Owing to this inertia, a variation of the resistance is not perceptible in the course of a period of the order of a single musical note. This eliminates all danger of distortion from deformation of the wave produced by a succession of musical notes. Such a distortion would appear, of course, if use were made of a resistance which would vary instantaneously, such resistances, for example, as can be formed from three electrode vacuum tubes. On the other hand, the variation of the resistance of the metallic filament used in the present case is subject to a time lag so that the device will change its amplification factor only if several notes in succession are played more softly or more

loudly than the passage immediately preceding them. This system has been found to be incomparably superior to the usual manual systems of regulation in which an operator watches a measuring instrument indicating the intensity at the output of the amplifier and increases or decreases the volume by manipulating suitable controls. In such a system the operator almost invariably corrects the faults in the reproduction of sounds only after they have become apparent in the broadcasting. Under the present system, however, while the resistance does not change quickly enough to cause distortion in the musical notes it, nevertheless, changes so quickly that too much or too little volume is automatically corrected before it becomes apparent to listeners.

While I have disclosed my invention in connection with a particular circuit arrangement, it will be obvious to those skilled in the art that it is adapted to many modifications and to many different uses. I intend to be limited, therefore, only as indicated by the scope of the following claims:

Claims—

1. An amplifying system comprising an amplifying device and a resistance having a positive temperature coefficient connected therewith, said resistances being so connected with the device that it varies the amplification factor of the alternating current component in inverse ratio to the applied energy and additional means to prevent the direct current component from flowing through said resistance.

2. A multi-stage amplifier comprising a plurality of connected amplifying devices and means including an element having a positive temperature coefficient of resistance connected between two successive stages, said means being so connected that it varies the amplification of the alternating current component across said stages inversely to the amount of energy applied thereto and additional means to prevent the direct current component from flowing through said resistance element.

3. A multi-stage amplifier comprising a plurality of connected amplifying devices and a resistance possessing a positive temperature coefficient of a predetermined value connected between two successive stages, said resistance being so connected that it varies in value with persistent variation in the current therethrough for varying the amplification across said stages in accordance with the energy applied thereto and additional means for preventing the flow of direct current through said resistance.

4. A multi-stage amplifier comprising a plurality of tubes connected in cascade, a resistance connected in series, between two adjacent tubes, with an element coupled to the anode circuit of one of said adjacent tubes

and another element coupled to the input circuit of the other of said adjacent tubes, said resistance having a positive temperature coefficient of resistance of a value which changes 5 in magnitude with variations of current therethrough whereby the amplification across said tubes varies inversely to the applied energy for persisting changes in the amount of energy, but not for instantaneous 10 changes and additional means to prevent the flow of direct current through said resistance.

5. In an audio frequency amplifying system, in combination, an aperiodic link circuit connected between two successive stages, and 15 means having a positive temperature coefficient of resistance included in said link circuit, whereby the amplification factor of the alternating current component varies inversely with the applied energy to be amplified.

6. In a two-stage audio frequency amplifying system, the combination with an aperiodic link circuit connected between said stages, of a resistance having a positive temperature coefficient in said link circuit of such 20 value that increase in input energy will effect a decrease in the amplification factor of said system.

7. A multi-stage amplifying system, comprising a link circuit connected between successive stages and a resistance having a positive temperature coefficient in each of said link circuits of such value that increase in 25 input energy will effect a decrease in the amplification factor of said system.

8. In a two-stage audio frequency amplifying system, in combination, an aperiodic link circuit connected between said stages, a resistance having a positive temperature coefficient in said link circuit whereby blasting is effectively eliminated, and a 30 damping resistance connected in the input circuit of the last stage.

9. A multi-stage amplifier comprising a plurality of cascade connected vacuum tube 35 amplifiers, a resistance connected between successive stages, said resistance changing in value with variations of current therethrough, whereby the degree of amplification 40 across said amplifiers varies inversely to the applied energy for persisting changes in the amount of energy but not for instantaneous 45 changes.

10. In an audio frequency amplifying system, a transformer, a resistance, a second transformer, means for utilizing energy, and means to furnish energy to the primary of the first transformer, the secondary of the first transformer being connected in series 50 and forming a closed circuit with the resistance, and with the primary of the second transformer, the secondary of the second transformer supplying energy to the utilizing 55 means.
